UNITED STATES PATENT OFFICE.

WILLIAM T. MERSEREAU, OF ORANGE, NEW JERSEY.

DESIGN FOR BRASS TUBING.

Specification forming part of Design No. **11,530**, dated December 2, 1879; application filed October 13, 1879.
[Term of patent 14 years.]

To all whom it may concern:

Be it known that I, WILLIAM T. MERSEREAU, of Orange, Essex county, New Jersey, have invented and produced a new and original Design for Brass Tubing to be employed in the manufacture of stair-rods, chandeliers, and bedstead-posts and cribs; and I do hereby declare that the following is a specification of my design, reference being had to the accompanying drawings, and to the letters of reference marked thereon, in which—

Figure 1 is a view of a section of tubing made in accordance with my design; Fig. 2, a view of the opposite side of the same. Fig. 3 is a top view of the same.

In the drawings like parts of the design are indicated by the same letters of reference.

The nature of my design consists in making

brass tubing for the manufacture of stair-rods, chandeliers, and bedstead-posts and cribs in imitation of bamboo; and for this purpose the tubing A is ornamented with the longitudinal groove *b* and the raised portions or encircling-rings *c*.

Having now set forth my invention, what I claim as new, and desire to secure by Letters Patent, is—

The design for brass tubing, formed by ornamenting the same with the longitudinal groove *b* and the encircling-rings *c*, substantially as set forth.

WILLIAM T. MERSEREAU.

In presence of—

GEORGE W. HOLT,

WILLIAM V. H. HICKS.
